United States Patent Office

Des. 186,615
Patented Nov. 10, 1959

186,615

CLOCK

Gordon Florian, Bridgeport, Conn., assignor to Sunbeam Corporation, Chicago, Ill., a corporation of Illinois

Application August 7, 1958, Serial No. 52,111

Term of patent 14 years

(Cl. D42—7)

Fig. 1 is a front perspective view of the clock showing my new design;

Fig. 2 is a top plan view thereof;

Fig. 3 is a right-side elevational view thereof; and

Fig. 4 is a fragmentary vertical section on the line 4—4 of Fig. 2.

The dominant features of the design reside in the portions shown in full lines.

I claim:

The ornamental design for a clock, as shown and described,
